UNITED STATES PATENT OFFICE.

HUGO R. SCHMITT, OF NEW YORK, N. Y., ASSIGNOR TO WESTERN ELECTRIC COMPANY, INCORPORATED, OF NEW YORK, N. Y., A CORPORATION OF NEW YORK.

CARRIER-WAVE TRANSMISSION.

Application filed May 12, 1923. Serial No. 638,461.

This invention relates to carrier wave transmission, and more particularly to methods and means for the secret transmission of radio signals.

5 An object of the invention is to provide radio communication systems which combine, to a greater degree than prior systems, efficient utilization of electric energy, economy of frequency range and secrecy.

10 A feature of the invention relates to an improved method of signaling with a single signal side band without the unmodulated carrier wave, comprising utilizing the local transmitting source to provide the carrier frequencies which are necessary for reception.

15 To give an added measure of secrecy, the frequencies of the carriers for two-direction transmission may be synchronously varied, as, for example, by a printing telegraph apparatus at the respective stations, or the signal band may be inverted in frequency and synchronized variations similarly caused to occur in the inverted waves.

Another feature relates to the transmission of a suppressed carrier, signal modulated, wave in which the carrier frequency is continuously varied at one or both of the stations, as by means of printing telegraph apparatus, and in which the carrier wave is reproduced at the receiving station without the use of local sources.

Additional features are an efficient arrangement for impressing the carrier wave on the grid of an electric discharge modulator and a compensating means in the output circuit of the modulator to maintain the desired squared characteristic under operational conditions.

Communication by use of single side band, suppressed carrier, transmission has the element of secrecy inherent in suppressed carrier systems generally, and in addition the advantages of relatively great economy of power and of frequency range. The use of at least two stages of amplification at the transmitter is desirable in order to effect the complete separation of one side band from the other components. Applicant proposes to utilize one of the local sources required for this function to supply the incoming carrier for reception. If the difference frequency method of receiving is used, a combination of the waves from the

two local sources may be used to supply the transmitted carrier at the receiver. 55

In a modified form of the single side band suppressed carrier transmission system, designed to increase the degree of secrecy, the frequencies of the unmodulated carrier components are synchronously varied at the two stations. This may be accomplished by means of a printing telegraph apparatus, which may also supply a secret telegraph channel. Since synchronization insures the continuance of the initial frequency relation between the oppositely directed waves, even when the frequency is varied, the mode of reception above described, in which the local transmitter sources are utilized for reception, may be used. A somewhat similar 70 secrecy system is provided by inverting the frequencies of the signal wave and synchronously varying the frequencies of the inverted waves at the two stations by means of the printing telegraph apparatus. 75

In an alternative secrecy system characterized by suppressed carrier transmission and in which the carrier is continuously varied, synchronization of the variations at the two stations is not attempted, but the carrier is reproduced at the receiver by derivation from a minute amount of carrier which is independently transmitted for that purpose. The difference frequency method of reception is used to obtain a separable frequency 85 component derived from said carrier, which may be amplified and combined with the minute portions of the incoming carrier to produce the carrier in sufficient amount to be used for detection. 90

An improved form of balanced modulator permits the carrier wave to be more directly impressed on the input electrodes thus avoiding shunting through the distributed capacity of the low frequency transformer. 95

A further improvement in modulator circuits relates to the use of a compensating tube having characteristics similar to those of the modulator tube or tubes, in the space current path of such modulator. The impedance of this tube varies with that of the modulator tubes. This insures that the potential impressed on the plates of the modulator remains constant during modulation. 100

The invention may now be more fully understood from the following detailed de-

- scription when read in connection with the accompanying drawing, Figs. 1, 2, 6, 7 and 8 of which constitute circuit diagrams of two-way radio communication stations embodying the invention, Fig. 3 of which illustrates a detail of the system of Fig. 2, Figs. 4 and 5 of which, together with Fig. 2, constitute another modification of the invention, Fig. 9 illustrates a modulator circuit adapted to be used with any one of the modifications of the invention, Fig. 10 illustrates a further improvement in modulator circuits and Fig. 11 illustrates a circuit which may be substituted for the balanced modulator and its associated selective circuit in any one of the signaling systems disclosed. In these figures, reference characters which suggest the functions of the respective elements are used. For example, A, BAL M, BF, LF and HO will be used to indicate respectively an amplifier, balanced modulator, band filter, low pass filter and a high frequency oscillator.
- Fig. 1 discloses the circuits used at each station of a difference frequency two-way radio communication system which is characterized by suppression of the unmodulated carrier wave component and single side band transmission. The circuits at the left of antenna AN are used for transmission, those at the right for reception. The operation of the transmitting circuit is as follows:
- Speech or other signal waves from source 1 are limited by low pass filter LF to their essential frequency range and impressed together with a wave from intermediate frequency oscillator or oscillator-amplifier IO on balanced modulator BAL M. The resulting modulated intermediate frequency carrier wave is transmitted by this modulator free from any unmodulated carrier frequency component to the band filter BF, which selects a single side band. It will be assumed that the upper side band is the one selected, although either side band may be selected. The label $f+S$ indicates that this side band has a frequency which is equal to the sum of the intermediate carrier frequency f and that of the signal S . This side band is used to modulate a wave from high frequency oscillator HO in a second balanced modulator BAL M₁. A single side band of the modulated wave, comprising, in the case assumed, frequencies of $F+f+S$, is selected by band filter BF₁, amplified by power amplifier PA, and radiated from antenna AN. This wave is in effect the upper side band of a radio frequency carrier wave, having the frequency $F+f$. This radio carrier frequency will be designated C. The received wave is similar in characteristic to this transmitted wave and may be similarly represented as comprising the radio carrier C₁ modulated by a signal S₁. Assuming, for the moment, that waves of frequencies C and C₁ are supplied respectively by circuits 2 and 3, the received wave C₁+S₁ is detected and the signal indicated by the following sequence of steps:
- Detection by high frequency detector HD 70 yields a difference, or intermediate, frequency C-C₁ and the signal modulated difference frequency C-C₁-S₁; these waves are amplified by intermediate frequency amplifier IA and detected in intermediate frequency detector ID, which yields among other components a signal S₁, which, after amplification by amplifier SA, is indicated in telephone receivers 4.
- It should be noted that detection by detector HD also yields signal S₁, so that the detection in this stage alone may, if desired, be relied on to reproduce the signal. However, the difference frequency method, as described above, is much to be preferred on account of the amplification and increased selection thereby made possible. In particular, the ether might contain signal bearing carrier waves whose frequencies so nearly approximate the frequency of the desired wave that they could not be separated therefrom by antenna tuning. In this case detection in one stage would result in the superposition of two or more signal waves in the output of detector HD.
- An important feature of the invention is a means for obtaining the two radio carrier waves required for reception without recourse to the use of local sources other than those necessarily required for transmission from the same station. The radio carrier wave of frequency C is obtained by combining the waves from the two local sources IO and HO in modulator M and selecting the upper side band F+f by band filter BF₂. The radio carrier C₁ is obtained directly from source HO, the frequencies of the intermediate and high frequency carrier waves making up the radio carrier wave transmitted from the distant station being adjusted accordingly. The necessary relation of frequencies, in order that the above described operation may be performed identically at the two stations, will be satisfied, if the following frequencies are used at the respective stations: the wave transmitted from station A=C+S=F+f+S; the wave transmitted from station B=C₁+S₁=F₁-f₁+S₁; F=C₁-f₁; F₁=C=F+f; f=f₁. It should be noted that the use of identical circuit arrangements at both stations requires that after each stage of modulation side bands of opposite sign be used for the two stations.
- The system described is characterized by relatively great economy of power, economy of frequency range, a minimum of elements for two-way operation with single side band transmission, and secrecy to the extent that an interceptor must have a properly adjust-

ed local source in order to obtain intelligible reception.

Fig. 2 illustrates an improvement over the system of Fig. 1 characterized by greater secrecy. This results from the use of a variable high frequency carrier. It is not necessary to use single side band transmission or successive modulation, although these features are desirable. If successive modulation is used, the frequency variation of the radio carrier wave may be secured by variations in the first instance in the wave from either the intermediate or high frequency carrier source. The frequency variation can be accomplished very simply by the means disclosed in Fig. 3 in which there is shown an oscillator, the frequency of which is determined by the constants of a tuned circuit. This circuit includes a condenser varied periodically as disclosed in Canadian patent to Beatty Serial No. 197,181, patented February 10, 1920.

For the most complete measure of secrecy, the variation may be caused to occur at each of the two stations, although, of course, the advantages of this system may be realized in part if the variation occurs at one station only. The receiving circuit would be the same for both cases.

The circuit arrangement disclosed in Fig. 1 for obtaining the interacting frequency wave for reception cannot be used in this system, since the frequency relation between the incoming and outgoing frequencies, which is a necessary feature of such system, would require synchronous variations at the two stations. In order to obtain this interacting frequency wave a very minute amount of unmodulated radio carrier is transmitted by combining a small portion of the outputs of the two oscillators HO and IO in modulator M, selecting the upper side band by band filter BF_2 , and impressing it on the input of the power amplifier PA. This unmodulated component is insufficient in amount to permit signal detection by any ordinary means. It would be practically impossible to separate it from its side bands at the receiver for the purpose of amplifying it sufficiently to permit of normal detection. Detection in high frequency detector HD gives a minute amount of difference frequency carrier wave. This difference frequency $C - C_1$ may be readily separated from its signal side bands, amplified in amplifier A and impressed on the input of the detector HD. The combination of this amplified difference frequency with the minute incoming radio carrier C in the detector gives sufficient amounts of the radio carrier C_1 for detection. Detection is accomplished by detector HD, after amplification, if desired, by a high frequency amplifier HA. The detector signal may be amplified by

speech amplifier SA and indicated by telephone receiver 4.

The system of Fig. 2 modified by the substitution of the circuits of Fig. 4 for the circuits shown at the left of line X—X, and by the substitution of the circuits of Fig. 5 for the circuits shown at the right of line Y—Y, provides for all of the functions of the system of Fig. 2 and an additional printing telegraph channel.

The speech frequency band in this modification of Fig. 2, is limited by band filter BF_3 to frequencies above a lower limit high enough to permit the use of a telegraph frequency. For example, the filter may pass frequencies between 200 and 2000 cycles. Low frequency oscillator LO and low pass filter LF_1 supply a current of a low frequency, for example 100 cycles, for printing telegraph transmission and for synchronizing the rotating parts of the printing telegraph transmitter and receiver at the respective stations. This current is applied to the printing telegraph transmitter and synchronizing apparatus P. The telegraph frequency output current is impressed together with speech current and the current from source IO, on the balanced modulator BAL M. The frequency of the current from the high frequency oscillator HO is varied synchronously from the moving parts of the printing telegraph apparatus in any well known manner. As in the system of Fig. 2, the variations may be caused to occur in the frequency of either oscillator HO, as disclosed, or of the oscillator IO. By using an irregular shaped condenser plate as e. g. that disclosed in Canadian patent to Beatty Serial No. 197,181, patented February 10, 1920, a complex variation of frequency can be produced which would be exceedingly difficult for an interceptor to reproduce in his local oscillator.

A type of printing telegraph apparatus that may be used, with the changes incident to operation in a radio communication system, is described in a paper by John H. Bell, printed in the "Transactions of the American Institute of Electrical Engineers", volume 39, part 1, page 166, in which see the subject matter under "Multiplex system," page 193. The system there shown is adapted for the use herein proposed by merely replacing the direct current synchronizing and signaling sources by alternating current source LO and by completing the circuit from this source through the printing telegraph transmitter at the transmitting station so that the telegraph currents may be utilized as modulating currents in the manner customary in radio transmission circuits. If desired, different frequencies may be used for synchronizing and for telegraph signaling.

The detected low frequency currents at line Y—Y of the modified receiver of Fig. 2 contain components corresponding to speech and the telegraph currents delivered from the output circuit of apparatus P. These are separated by band filter BF_4 and low pass filter LF_2 . The speech is indicated by telephone receivers 4 and the telegraph and synchronizing currents are impressed on the printing telegraph apparatus P_1 which comprises the usual synchronizing and recording apparatus for a printing telegraph receiver. The use of a printing telegraph apparatus makes possible simultaneous secret transmission of telephone and telegraph signals since the telegraphic message is in the printing code and both the telephonic and telegraphic messages are transmitted by a varying frequency carrier wave.

The use of a synchronizing means insures a constant difference between the carrier frequencies of the waves transmitted in the two directions. Accordingly, the carrier wave may be supplied by derivation from the transmitter sources as in the system of Fig. 1 instead of by the arrangement disclosed in Fig. 2. Circuits for accomplishing this are illustrated in Figs. 6 and 7. The transmitting circuit of Fig. 6 is the same as that of Figs. 2 and 4 except that the radio carrier frequency is varied by varying the frequency of the intermediate, instead of the high frequency, source. The receiving circuit is like that of Fig. 1 but instead of a difference frequency receiving circuit simple detection is used, the frequencies being the same for transmission in both directions. If the difference frequency receiving circuit were used, the wave from the high frequency oscillator and the combined wave from the two oscillators could similarly be used to supply respectively the incoming and outgoing radio carriers. As in the system of Fig. 2, the frequency variations may be caused to occur in the wave from either of the two oscillators.

Fig. 7 illustrates a system which is the same as that of Fig. 6 except that a single stage of modulation is used. Elements similarly designated have the same functions as the corresponding elements in Fig. 6. Since the use of modulator M is not necessary the amplification incidentally afforded thereby may be secured if necessary by amplifier A_1 . On account of the difficulty in effecting separation of the side bands at the high frequency used for radio transmission, such separation would in general be less perfect than if the system of Fig. 6 were used. The circuit of Fig. 7 could be effectively used if it were not attempted to obtain the advantages incident to single side band transmission, but if both side bands were transmitted. This could be accomplished by merely eliminating the filter BF_1 ,

or by substituting therefor a filter which passed substantially both side bands.

Fig. 8 illustrates the low frequency circuits at a two-way radio communication station in which secrecy is obtained in part by speech inversion and in part by variation of the frequency of the inverted speech, this variation resulting from a variation of the frequency of the inverting source. A printing telegraph apparatus is used to produce synchronized variations of the inverting frequency at the transmitter and of the re-inverting frequency at the receiver in addition to its normal function as a part of a printing telegraph channel. The speech inversion system operates according to the method disclosed in British Patent No. 179,016.

The frequencies of the two sources at the transmitter must, of course, be equal at all times to the corresponding stepping up and re-inverting sources at the distant receiver. In the system herein disclosed, the printing telegraph synchronizes the frequencies of the variable sources at the two stations. Common sources serve for the transmitting and receiving circuits at each station and common modulators for the transmitting and receiving functions of each station.

Speech from microphone 1 or the like is limited by low pass filter LF_3 as in the systems of Figs. 6 and 7 in order to provide space for the synchronizing and telegraph frequencies. The resulting speech band is impressed with current from oscillator O on the balanced modulator $BAL\ M_2$, which, together with band filter BF_5 , eliminates all the frequency components except the upper side band, the frequency of which may be of the order of 9000 to 11,000 cycles. Instead of a balanced modulator, a simple modulator may be used, reliance being had on the filter to eliminate the carrier frequency. This side band is impressed with current from oscillator O_1 on the second balanced modulator $BAL\ M_3$. The frequency of oscillator O_1 is varied by the printing telegraph apparatus, as in the previously described systems. With the assumed value of the modulated side band the current from oscillator O_1 may be given a frequency varying from 11,100 to 11,600. The lower side band is in effect an inverted speech band which varies from substantially its normal frequency range 100 to 2100 cycles to the range from 600 to 2600 cycles. The preliminary stepping up by the modulator $BAL\ M_2$ before inversion is for the purpose of providing a more complete separation of the band to be inverted and accordingly to avoid the presence of interfering components which would otherwise result from the inverting operation. This variable inverted speech is selected by band filter BF_6 and utilized, with the telegraph tone and syn-

chronizing current, in subsequent steps of modulation and radiation, which steps may conform to any of the conventional usages of radio transmission, as illustrated in part, 5 for example, in Figs. 1 and 2.

Waves incoming from the radio receiving circuit, which may, as in the case of the transmitting circuit, conform to any of the conventional usages of radio reception, as 10 illustrated, for example, in Figs. 1 and 2, are separated into its inverted speech and telegraph note components by band filter BF_7 , and low pass filter LF_4 . The latter is impressed on the printing telegraph synchronizer and recorder P_1 . The inverted speech is stepped up by combination with the current from oscillator O_1 in balanced modulator $BAL\ M_1$, the upper side band being selected by band filter BF_8 , which is identical 15 in all respects to band filter BF_5 . Re-inverted speech is obtained from this side band by combination with a current from oscillator O in balanced modulator $BAL\ M_2$. The resultant current contains current of the 20 telegraph note as well as of speech. Speech current is separated by the band filter BF_9 , and indicated in telephone receivers 4.

The printing telegraph apparatus at one circuit may be considered as a master controlling means, the other circuits at the two stations both transmitting and receiving, being provided with means for keeping their printing telegraph apparatus in synchronism therewith. Accordingly, it is immaterial 25 as to which telegraph apparatus is used at each station to cause the oscillator frequency variations. As a matter of practice, the rotating parts of the printing telegraph apparatus for transmitting and receiving at 30 each station are usually mechanically coupled.

Fig. 9 illustrates the circuits of a novel form of modulator which may be used in any one of the systems of the invention. 45 The modulator is of the balanced type.

In the specific circuit arrangement of the figure, the tubes 5 and 6 are alike and of the usual three-electrode type. These tubes are related as in the balanced modulators disclosed in Fig. 3 of Espenschied Patent No. 50 1,447,204, issued March 6, 1923, except for the arrangement of the carrier wave input circuit. The circuits and theory of operation of this generic type of balanced modulator 55 are described in Carson Patent No. 1,343,307, issued June 15, 1920, to which reference is made for a more detailed disclosure.

In vacuum tube circuits generally it has 60 become the practice to ground one of the terminals of a cathode as at 7 in order to prevent undesirable fluctuations in the capacity between the parts of the circuit and ground. It has been found that, when using the ground, if the carrier current is impressed

on the input electrodes of the tubes by means 65 of a connection to the common input lead, the capacity between the modulating current input coil and ground, and other capacities, either intentionally used or unavoidably present between the input electrodes and ground, tends to shunt the carrier current from the input electrodes, necessitating a greater amount of input energy to maintain the input electrodes at the desired potential. It also results from the use of this connection 70 that there is an undesired variation of such potential. This shunting effect increases with the frequency of the carrier currents so that in certain radio frequency circuits, as in the high frequency balanced modulators elsewhere disclosed in this application, an abnormal amount of input energy is required.

This effect is avoided in the present circuit by connecting the carrier input circuit 85 directly to the input electrodes through large capacity condensers 9 and 10 which are large enough to constitute small impedances to the carrier frequency but small enough to prevent any appreciable flow of 90 modulating current in this circuit. The shunting effect is accordingly avoided and the input electrodes receive the full variation of potential which exists in the secondary of transformer 11 unaffected by the electrical condition of the modulating or other circuits. It is desirable although not essential 95 to provide high frequency choke coils 12 and 13 to prevent the carrier current from flowing in the speech input circuit. The use of separate input circuits for the carrier and modulated frequencies, with these condensers and choke coils, insures a complete independence of function of these circuits. It should be noted that although the invention 100 has been embodied in a balanced modulator circuit, it may be similarly embodied in a simple modulator having a grounded cathode.

Fig. 10 illustrates a further improvement 110 of a balanced modulator circuit. The improvement consists in the addition of the compensating tube 14 and the circuits associated therewith to a balanced modulator circuit.

To effectively suppress transmission of the unmodulated carrier component a balanced modulator requires that the characteristic curves of the two modulator tubes, during 115 modulation, be identical. The condition of a modulating tube space current circuit during modulation is similar to that of a variable impedance in series with a fixed impedance across a constant potential source. The potential at the junction of the two impedances varies as the resistance varies to constitute a variable fraction of the whole impedance. Applicant proposes to cause a cor- 120 125

responding variation of the otherwise constant external impedance and accordingly to keep the ratio of the internal and external impedances, and therefore the potential on the plates, constant. This permits tubes which are balanced under static conditions to be balanced under working or modulating conditions.

Compensating tube 14 has characteristics similar to those of modulator tubes 15 and 16. Its input circuit is subjected to similar variations of potential by circuit 17. Its internal plate-filament circuit accordingly has corresponding variations of impedance. Since the impedance of this internal plate-filament circuit is in series with the corresponding impedances of the modulating tubes, it results that the division of potential drop between the internal plate-filament circuits of the modulator and the remaining part of the space current circuit thereof, including the compensating tube, remains constant. The potentials impressed on the plates of the modulator tubes accordingly remain substantially constant.

The compensating tube may be used to compensate for the effect of the resistance of the space current source itself if this source is directly connected to the plates of the modulator. As used in the circuit of Fig. 10, it would compensate for the effect of that resistance plus the resistance of the output coils. It is especially useful to replace a comparatively large loading resistance which would otherwise have to be used in order to make possible the use of a space current source of higher potential than that for which the tubes are adapted. In this last case as well as where the modulator output circuit contains considerable resistance in addition to that furnished by the compensating tube, the constants of this tube would be chosen so that the variations in its internal plate-filament impedance are somewhat greater than the corresponding variations of the modulator.

Although particularly useful in a balanced modulator, as explained, the compensator may be similarly used in a single tube modulator to prevent the distortion which would otherwise result from the flattening of the characteristic curve during operation, and Fig. 10 is equally intended to illustrate this use. This result is secured by the operation of the compensating tube in maintaining the direct current plate potential constant. The same function may be accomplished in an amplifier tube arrangement as by emitting the carrier frequency circuit 18. Its use in this circuit would result in less distortion of the amplified wave and thus be additive to that ordinarily obtained with balanced amplifiers. Of course the compensating tube would have an equally important function in a single tube amplifier.

Although the use of a balanced modulator followed by a selective circuit has been illustrated in each of the figures which disclose single side band suppressed carrier transmission, reliance may be had on a selective circuit alone to eliminate the carrier and one side band. Fig. 11 illustrates one circuit for accomplishing this function. M_1 may be any modulator adapted to produce a modulated carrier wave comprising an unmodulated carrier component and the upper and lower modulation side bands. Circuits 19 and 20 are tuned respectively to one side band and the unmodulated carrier frequency and effectually eliminate these components from the output of the filters. Circuit 21 is tuned to the desired side band and accordingly resonantly selects and accentuates this component. This filter circuit is especially adaptable to a modulating system in which the modulating wave has either a single frequency or comprises a relatively narrow band of frequencies.

It will be understood that the details of the circuits and methods herein set forth may be embodied in organizations widely different from those illustrated without departing from the spirit of the invention which is defined in the following claims.

What is claimed is:

1. The method of efficiently modulating two waves wherein is used an electronic valve modulator having a grounded cathode and a control electrode, which comprises impressing one of said waves on the cathode and control electrode, and independently and directly applying the other wave to said cathode and control electrode, whereby any shunting to ground of either wave at a point anterior to said control electrode cannot affect the potential impressed thereon. 95

2. A translating device having an element substantially at ground potential for high frequency currents, input electrodes for said device including said element, means to impress on said input electrodes high frequency potentials, means to impress thereon low frequency potentials, and means to prevent the dissipation of the high frequency current through the capacity to ground of said low frequency impressing means from affecting the values of said impressed high frequency potentials. 110

3. The combination of an electronic valve modulator having a grounded heated cathode, an anode, and a control electrode, a modulating circuit connected to the cathode and control electrode, said modulating circuit having a capacity to ground in parallel with the control electrode, a source of current of high frequency and means connecting said source to the cathode and control electrodes in such manner as to prevent said capacity from shunting the carrier currents from the control electrodes. 120 125 130

4. A modulator comprising in combination an electron discharge device having a grounded cathode, an anode and a control electrode, an input circuit connected to the cathode and control electrode, means to couple a source of modulations to said input circuit, a second input circuit connected to the cathode and control electrode, means for coupling a source of high frequency oscillations to said second input circuit, and means whereby currents of the modulating and high frequencies are each confined to their respective individual circuits. 30
5. The combination of a modulator having two electronic valves each having a grounded heated cathode, an anode, and a control electrode, parallel input circuits for said valves including means connecting the cathodes and individual paths connecting said cathodes and the individual control electrodes, a source of modulating signal current variations associated with the individual paths, a direct high frequency connection between the control electrodes of said valves, and a source of high frequency oscillations connected between said control electrode connecting circuit and the cathodes, 35
6. A modulating system comprising a pair of translating devices having input and output electrodes, a circuit containing a source of high frequency energy, a circuit containing a source of low frequency modulating energy, means for symmetrically associating said high frequency circuit with said input electrodes, means for oppositely associating said low frequency circuit with said input electrodes, and an output circuit differentially associated with said output electrode circuits, said high frequency associating means comprising a circuit directly connected to said input circuits in parallel and including blocking condensers to prevent the current from modulating source from flowing therethrough. 40
- 50

In witness whereof, I hereunto subscribe my name this 11th day of May A. D., 1923.

HUGO R. SCHMITT.
